ELECTRIC COFFEE MAKER

William J. Rakocy, Clifton, N.J., assignor to North American Philips Corporation, New York, N.Y.

Filed Jan. 10, 1974, Ser. No. 432,305

Term of patent 14 years

Int. Cl. D7—02

U.S. Cl. D7—62

Fig. 1

Fig. 2

Fig. 3

Fig. 4

Fig. 5

Fig. 6

FIG. 1 is a front elevational view of an electric coffee maker showing my new design:

FIG. 2 is a left side elevational view thereof;

FIG. 3 is a right side elevational view thereof;

FIG. 4 is a top plan view thereof;

FIG. 5 is a rear elevational view thereof; and

FIG. 6 is a bottom plan view thereof.

The coffee pot may occupy different positions as indicated with the handle extending to the left in FIG. 1, extending forward in FIGS. 2 and 3, and extending at a diagonal in FIG. 4.

I claim:

The ornamental design for an electric coffee maker, as shown and described.
